M. McD. WILLIAMS

COMBINATION FOOT SWITCH

Filed Sept. 15, 1924

FIG. 1.

FIG. 2.

Inventor:

M. McD. Williams.

By *Edmund H. Lany*
his Attorney.

UNITED STATES PATENT OFFICE.

MARSHALL McD. WILLIAMS, OF FAISON, NORTH CAROLINA.

COMBINATION FOOT SWITCH.

Application filed September 15, 1924. Serial No. 737,897.

The present invention relates to circuit controlling switches, and particularly to such switches used for controlling the lights of an automobile.

5 An object of the present invention is to provide a switch or circuit-controlling device particularly adapted for placing the bright lights and dim lights in circuit, according to the situation in which the driver

10 finds himself.

Another object of the invention is to provide a switch for this purpose by which the driver can place in circuit either the dim or bright lights without glancing away

15 from the roadway and without removing his hands from the steering wheel.

A further object is to provide a device for this purpose which will enable a driver to control the lights of an automobile by

20 moving his foot.

A still further object of the invention is to provide a foot switch for the purpose stated, which is adapted to act also as a foot rest in connection with the accelerator.

25 Still further objects and advantages of the invention will appear from the following detailed description, taken in connection with the accompanying drawings which illustrate a preferred embodiment of the invention, and in which:

Figure 1 is a view partly diagrammatic and partly in vertical cross-section, and showing a circuit controlling switch in accordance with the present invention;

25 Fig. 2 is a top plan view of the switch housing shown in Fig. 1; and

Fig. 3 is a sectional view taken on the line 3—3 of Fig. 1.

Referring in detail to these drawings, the

40 reference-numeral 11 indicates a switch housing having a flat top-portion 12, vertical end walls 13 and 14 and end flanges 15 and 16. The end flanges 15 and 16 may be provided with holes adapted to receive

45 bolts, screws, or other securing means by which the housing 11 may be secured to the floorboard of an automobile. The housing 11 is preferably mounted in proximity to the foot accelerator 17, and the top-portion

50 12 may conveniently serve as a steady foot rest while operating said accelerator.

An operating rod 18 passes loosely

through an opening in the vertical wall 19 of a stationary supporting plate 20, which may be fixedly secured to the under side 55 of the top 12 by screws 21, and the rod 18 also passes through another opening 22 in the end wall 14 of the switch housing. Both openings are preferably square and the rod 18 is preferably square in cross section, as 60 shown in Fig. 3, to prevent rotation of the rod in the openings while still allowing it to reciprocate therein.

The rod 18 has a portion extending outside of the switch housing 11, which is 65 bent upwardly, as shown at 23, and terminates in an enlarged foot-engaging portion 24 which extends upwardly beyond the top of the housing. The other end of the rod 18 is preferably screwthreaded for the reception of a nut 25 by means of which a short downwardly extending arm 26 is retained on said rod. A coil spring 27 loosely encircles the rod 18 between the arm 26 and the vertical wall 19 of the guide plate 20 70 75 and tends to maintain said rod in the position shown in Fig. 1. A notch 28 having one vertical wall and one sloping or beveled wall is provided in the upper surface of the rod 18, and a flat spring 29 secured to 80 the inside of the switch housing 11 on the end wall 14, has its free end in contact with the underside of the rod 18, and acts to force said rod upwardly.

The rod 18 is thus maintained normally 85 in the position shown in Fig. 1 by the coil spring 27. When the driver moves the rod toward the right, by moving the enlarged end 24 in that direction by his foot, the coil spring tends to return the rod to its 90 original position until the notch 28 arrives in the opening 22, at which time the flat spring 29 will cause the rod to move upwardly slightly. The notched portion of the rod in engagement with the adjacent 95 portion of the end wall 14 prevents return of the rod to its former position until the driver depresses the end 24 of the rod, which action releases the engagement of the notched portion of the rod with the end 100 wall 18 and allows the coil spring 27 to return the rod to its former position. It will thus be seen that the rod 18, together with the arm 26 carried thereby, are nor-

2 mally held in inner position by the coil spring, and that they may be moved to outer position by the operator's foot, where they will be held by the notch 28 until released by downward pressure on the end 24 of the rod, after which they will be returned by the spring 27 to their former position.

- 5 The arm 26 completes the dim light circuit in the forward or outer position of the rod 18, and the bright light circuit in the inner position of the rod 18, as follows:
- 10

15 A short screw threaded bolt 30 passes through the lower portion of the arm 26, and is preferably insulated from said arm by a non-conducting sleeve (not shown) and by insulating washers 31, the bolt and washers being held fast in the arm 26 by a nut 32 threaded on the end of the bolt. The 20 bolt thus moves forward and backward with the arm 26, and its ends form contacting members adapted to complete the bright and dim light circuits, respectively.

25 At one end of its travel the bolt 30 contacts with a spring 33, which is mounted on a bolt 34 secured in the wall 13 of the switch housing, but insulated therefrom. At the other end of its travel the bolt 30 contacts with a similar spring 35 mounted on a bolt 30 36 secured in the depending vertical portion 19 of the plate 20, but insulated therefrom.

30 The letter S indicates any usual or convenient form of switch, which may be mounted on the instrument board of the automobile, and which, in the position indicated in Fig. 1, completes the circuit controlling the bright lights.

35 A conducting wire 36 leads from the switch S to a battery B and is grounded at G. A second wire 37 leads from the switch S to the bolt 30, and is connected thereto so that the adjacent wire portion is not stretched taut but is adapted to move with the bolt 30 as the rod 18 reciprocates.

40 A wire 38 leads from the spring 33 to the immediate lamp circuit including the headlights L, the circuit being grounded at G'. A wire 39 leads from the spring 35 through the resistance R to the wire 38.

45 When the bolt 30 is disconnected from the spring 35, and contacts with the spring 33, the bright light circuit is completed, the switch S being assumed to be closed. In driving, when the operator desires to dim his lights, he moves the end 24 of the rod 18 toward the right (Fig. 1) with his foot, thus causing a break in the bright light circuit as the bolt 30 leaves the spring 33, and completing the dim light circuit as the bolt 30 50 contacts with the spring 35 by reason of the resistance R. The notched rod 18 remains in this position, as heretofore described, until the operator depresses the end 24, upon which the coil spring 27 moves the rod 18 55 back to its former position, breaking the

dim light circuit by the separation of the bolt 30 from the spring 35 and completing the bright light circuit by its contact with the spring 33.

60 By this construction a light control switch 70 is provided which can be operated by the driver without taking his eyes off the road, and without taking his hands off the wheel and fumbling for a switch, by a simple movement of his foot sideways along the 75 accelerator foot rest to dim his lights, and by a slight downward pressure to light his bright lights, the spring 27 causing the bright light circuit to be completed without further attention from the driver. 80

What I claim is:

1. A circuit controlling switch structure comprising a housing, a pair of stationary spring contacts therein, an L-shaped rod operatively mounted in the housing and having its short arm disposed exteriorly of the housing to permit manipulation thereof, a contact member carried by the rod and adapted to selectively engage said spring contacts, spring means on the rod normally 90 maintaining said member in engagement with one of the spring contacts and latch means for releasably maintaining said member in engagement with the other of the spring contacts. 95

2. A circuit controlling switch structure comprising a housing including a flat top, vertical end walls and side walls; a supporting wall depending centrally from said top; an L-shaped operating rod having its long 100 arm nonrotatably and slidably traversing the supporting wall and an end wall and its short arm extending above said top in position for actuation by the foot of an operator; spring contacts mounted in alinement on the supporting wall and the other end wall respectively; a contact member fast to and depending from the inner end of the rod and adapted to selectively engage said spring contacts; spring means normally 110 maintaining said contact member in engagement with one of the spring contacts and latch means releasable by movement of the rod for maintaining the contact member in engagement with the other of the spring 115 contacts. 120

3. A circuit controlling switch structure comprising; a housing including a flat top, adapted for use as a foot rest, vertical end walls and side walls and end flanges adapted to be secured to the floor board of an automobile; a supporting wall depending centrally from said top; an L-shaped operating rod having its long arm nonrotatably and slidably traversing the supporting wall and an end wall and its short arm extending above said top in position for actuation by the foot of an operator; spring contacts mounted in alinement on the supporting wall and the other end wall respectively; a 125 130

contact member fast to and depending from the inner end of the rod and adapted to selectively engage said spring contacts; spring means mounted on the rod between the supporting wall and the contact member normally maintaining said contacting member in engagement with one of the spring contacts and latch means releasable by movement of the rod for maintaining the contact member in engagement with the other of the spring contacts.

In testimony whereof I affix my signature,

MARSHALL McD. WILLIAMS.
